Primary Examiner — Susan Moon Lee*(74) Attorney, Agent, or Firm* — Sughrue Mion, PLLC**CLAIM**

The ornamental design for a semiconductor memory device, as shown and described.

DESCRIPTION

FIG. 1 is a perspective view of a semiconductor memory device showing our new design; and,

FIG. 2 is a top plan view thereof.

Broken lines and unshaded portions entirely contained within broken line are not claimed.

1 Claim, 2 Drawing Sheets(56)
